UNITED STATES PATENT OFFICE.

RODNEY D. DAY, OF HAVERFORD, PENNSYLVANIA, ASSIGNOR TO THE AMERICAN MOTOR BODY CORPORATION, OF PHILADELPHIA, PENNSYLVANIA, A CORPORATION OF DELAWARE.

CHASSIS-FRAME CONSTRUCTION.

Application filed May 10, 1924. Serial No. 712,186.

To all whom it may concern:

Be it known that I, RODNEY D. DAY, a citizen of the United States, residing at Haverford, in the county of Delaware and

5 State of Pennsylvania, have invented certain new and useful Improvements in Chassis-Frame Construction, of which the following is a specification.

This invention relates to chassis frame 10 construction, and more particularly relates to a chassis frame including a criss-cross or diagonal stiffening structure combined with a steady bearing for a propeller shaft.

In motor vehicles where the propeller 15 shaft is quite long or, in other words, where the distance between the gear set or transmission and the rear axle is quite long, it has been customary to construct the propeller shaft in sections, and, in such case, 20 there is need for a steady bearing, sometimes called a mid-bearing, to support a short portion or section of the propeller shaft at a median point between the gear set and the rear axle. Moreover, when the chassis frame 25 is quite long, it is desirable to stiffen the structure by means of stiffening members or braces arranged to extend between the two side rails of the frame, particularly when a rigid form of chassis is desired.

30 It is necessary to support a steady bearing in a very secure manner, and the principal aim of my invention is to provide means for supporting a median proportion of a propeller shaft on a chassis frame in a 35 secure manner, and in such a way that the propeller shaft will run freely, quietly, smoothly, and with a minimum of friction and without trouble.

Another object of my invention is to provide 40 a criss-cross stiffening structure for an automobile chassis frame, which is very effective.

A further object of my invention is to provide 45 a chassis frame construction which includes the combination of a very effective criss-cross or diagonal stiffening structure with a securely supported and efficient steady bearing for a propeller shaft.

50 Other objects will be in part obvious and in part pointed out hereinafter.

In order that a clearer understanding of my invention may be had, attention is hereby directed to the accompanying drawings

forming a part of this application and illustrating one possible embodiment of my invention. Referring to the drawings, Fig. 1 is a top view of a stiffening structure combined with a steady bearing for a propeller shaft and embodying this invention; Fig. 2 is a sectional view thereof and is taken on the line 2-2 of Fig. 1; and Fig. 3 is an enlarged sectional view of a portion of the construction and is taken on the line 3-3 of Fig. 1, the view being broken away at the center. Similar reference characters refer to similar parts throughout the several views of the drawings.

Referring to the drawings, the chassis frame comprises a pair of spaced longitudinal side members 1 and 2, which at their front may be connected by a cross brace 3. I place a criss-cross stiffening structure between the rails 1 and 2 and rigidly secure the structure to these rails, so that the frame will be effectively stiffened and braced. As shown, the stiffening structure presents four arms, 4, 5, 6 and 7, which approach each other at a common center and diverge therefrom in different directions, and each at its outer end is rigidly secured to a side rail. For instance, arm 4 may be secured to the rail 1, toward its rear, by means of plate 8 and rivets or bolts 9. Arm 5 may be secured to the rail 1, toward its front, by means of plate 10 and bolts or rivets 11. Arms 6 may be secured to the rail 2, toward its front, by means of plate 12 and bolts or rivets 13, and arm 7 may be secured to the rail 2, toward its rear, by means of plates 14 and rivets or bolts 15. The inner ends of these arms 4, 5, 6 and 7 may be secured together at a common center by means of plates 16 and bolts or rivets 17. The stiffening structure may also comprise a pair of cross members 18 and 19 which not only serve as means for further reenforcing the stiffening structure, but which at the same time constitute brackets for supporting bearings 20 and 21 for a median portion of a propeller shaft 22. Bracket 18, as shown, extends between the arms 5 and 6 and is secured thereto by means of bolts 23 while bracket 19 extends between the arms 4 and 7, and is secured to these arms by means of bolts 24.

The arms of the stiffening structure may

be made in individual units or, if desired, and as shown, the arms 4 and 5 may comprise the end portions of an integral member having a central portion 25 which is attached to the plates 16. Similarly, the arms 6 and 7 may comprise portions of a one piece member which has a central portion 26 which is secured to the plates 16.

It has been found that the angular 10 position of the arms 4, 5, 6 and 7 to a vertical plane passing through the longitudinal center line of the chassis may be varied from 15 degrees to 45 degrees and still retain an effective structure. As shown in the 15 drawings, these arms are disposed at a thirty degree angle to such plane. If the angle is more than 45 degrees, the arms of the stiffening structure would be so short toward the front and rear as not to be very effective in 20 stiffening the frame. If such angularity of the arms is less than 15 degrees, they are too nearly parallel with the side frames 1 and 2. Of course, in any case, the angularity of the arms cannot be less than the length of the 25 chassis frame will permit.

In order to properly and effectively accommodate the propeller shaft section 22 and the bearings therefor, each bracket 18 and 19 is preferably provided with an annular sleeve portion 27 forming a cup 28 adapted to suitably receive a bearing, such as a roller bearing 20 or 21, for the propeller shaft 22. Each bracket 18 and 19 is also preferably provided with a sleeve portion 29 through which the propeller section 22 is adapted to extend. If desired, a tubular guard or protecting sleeve 30 for the propeller shaft 22 may be mounted on the sleeves 29 of the brackets, so as to extend 40 therebetween and to effectually enclose the median portion of the propeller shaft.

The chassis frame members as well as the members of the stiffening structure and the steady bearing brackets are preferably metallic and of channel shape in cross section, although obviously the material and shape of these members may be varied considerably. Also, instead of using two brackets 18 and 19 to accommodate two steady bearings for 50 the propeller shaft only one bracket and one steady bearing may be employed, and such bearing may be disposed at any point along the portions 25 and 26 of the stiffening structure by securing a suitable bracket for 55 the steady bearing to these portions of the stiffening structure at the desired points.

From the above description it will be noted that the construction comprises an effective criss-cross or diagonal stiffening structure combined with a steady bearing for a propeller shaft, and that the steady bearing is very securely held in place, and is so arranged as to be conducive to the smooth running of the propeller shaft without 60 trouble.

As many changes could be made in the above construction and as many apparently widely different embodiments of this invention could be made without departing from the scope thereof, it is intended that all matter contained in the above description or shown in the accompanying drawings shall be interpreted as illustrative and not in a limiting sense.

What I claim is:—

1. The combination with a chassis frame stiffener, comprising a plurality of members including stiffening arms arranged in diagonal fashion, a bracket extending between and secured to two of said members, and a propeller shaft bearing carried on said bracket.

2. The combination with a chassis frame stiffener, comprising a plurality of members including stiffening arms arranged in diagonal fashion, of a steady bearing bracket extending between and secured to two of said members, said bracket having a sleeve portion, and a propeller shaft bearing seated in said sleeve portion.

3. The combination with a chassis frame stiffener, comprising a plurality of members including stiffening arms arranged in diagonal fashion, of a steady bearing bracket extending between and secured to two of said members, said bracket having a sleeve portion, and a propeller shaft bearing seated in said sleeve portion, and having another sleeve portion, and a propeller shaft portion extending therethrough and through said bearing.

4. In a chassis frame, a pair of spaced side rails and a plurality of stiffening members including arms arranged in diagonal fashion joined together at a common center and diverging therefrom in different directions toward said side rails and secured thereto, the angular disposition of said arms with respect to a vertical plane passing through the longitudinal center line of the chassis being between 15 degrees and 45 degrees, and a pair of spaced brackets secured to said stiffening members, each bracket having a cup portion, and a propeller shaft bearing seated in each cup portion.

5. In a chassis frame, a pair of spaced side rails and a plurality of stiffening members including arms arranged in diagonal fashion joined together at a common center and diverging therefrom in different directions toward said side rails and secured thereto, the angular disposition of said arms with respect to a vertical plane passing through the longitudinal center line of the chassis being between 15 degrees and 45 degrees, and a pair of spaced brackets secured to said stiffening members, each bracket having a cup portion, and a propeller shaft bearing seated in each cup portion, each bracket having also a sleeve portion, a pro-

propeller shaft portion extending through the sleeve portions of both brackets and through said bearings.

6. In a chassis frame, a pair of spaced 5 side rails and a plurality of stiffening members including arms arranged in diagonal fashion joined together at a common center and diverging therefrom in different directions toward said side rails and secured 10 thereto, the angular disposition of said arms with respect to a vertical plane passing through the longitudinal center line of the chassis being between 15 degrees and 45 degrees, and a pair of spaced brackets secured to said stiffening members, each bracket 15 having a cup portion, and a propeller shaft bearing seated in each cup portion, each bracket having also a sleeve portion, a propeller shaft portion extending through the sleeve portions of both brackets and through 20 said bearings, and a tubular cover member surrounding said propeller shaft portion and extending between and mounted on said sleeve portions.

This specification signed this 4th day of 25 May, 1924.

RODNEY D. DAY.
